[57] CLAIM

The ornamental design for a cigarette lighter, substantially as shown and described.

DESCRIPTION

FIG. 1 is a perspective view of a cigarette lighter showing my new design;

FIG. 2 is a front view thereof;

FIG. 3 is a rear view thereof;

FIG. 4 is a top plan view thereof;

FIG. 5 is a bottom plan view thereof;

FIG. 6 is a right side view thereof;

FIG. 7 is a left side view thereof;

FIG. 8 is a perspective view showing the lighter in the hipped-opened state;

FIG. 9 is a perspective view of a second embodiment of my design for a cigarette lighter;

FIG. 10 is a front view thereof;

FIG. 11 is a rear view thereof;

FIG. 12 is a top plan view thereof;

FIG. 13 is a bottom plan view thereof;

FIG. 14 is a right side view thereof;

FIG. 15 is a left side view thereof; and

FIG. 16 is a perspective view showing the lighter in the flipped-opened state.
